US00D637619S

(12) United States Design Patent
Viggers et al.

(10) Patent No.: US D637,619 S
(45) Date of Patent: * May 10, 2011

(54) PORTION OF A DISPLAY SCREEN WITH AN ICON

(75) Inventors: Kevin Viggers, Calgary (CA); Giselle Goncalves, Mississauga (CA); Julie LaFleur, Calgary (CA); Ron Desnoyers, Calgary (CA); Jenna Pipchuk, Calgary (CA)

(73) Assignee: SMART Technologies ULC (CA)

() Term: 14 Years

(21) Appl. No.: 29/342,235

(22) Filed: Aug. 20, 2009

(51) LOC (9) Cl. 32-00

(52) U.S. Cl. D14/492

(58) Field of Classification Search D14/485–495;

D18/26, 31–33; D20/11–12, 23–25, 29–32,

D20/36–38; 715/700–867, 973–977
